HANDBAG CLOSURE CLASP

Etienne Aigner, 217 Haven Ave., New York, N.Y.

Filed Jan. 24, 1961, Ser. No. 63,678

Term of patent 14 years

(Cl. D87—2)

FIG. 1 is a front elevational view of a handbag closure clasp, showing my new design;

FIG. 2 is a rear elevational view thereof;

FIG. 3 is a side elevational view thereof;

FIG. 4 is a vertical sectional view taken on the line 4—4 of FIG. 1;

FIG. 5 is a front elevational view of one of the members of the closure clasp; and

FIG. 6 is a front elevational view of the other of the members of the closure clasp.

I claim:

The ornamental design of a handbag closure clasp, substantially as shown.
